UNITED STATES PATENT OFFICE.

ALFRED L. BLOMFIELD, OF DENVER, COLORADO, ASSIGNOR TO THE DORR COMPANY, A CORPORATION OF DELAWARE.

FLOTATION ORE-SEPARATING APPARATUS.

1,310,051.

Specification of Letters Patent. Patented July 15, 1919.

Application filed July 15, 1916. Serial No. 109,503.

To all whom it may concern:

Be it known that I, ALFRED L. BLOMFIELD, a subject of George V, King of England, residing at Denver, in the county of Denver and State of Colorado, have invented certain new and useful Improvements in Flotation Ore-Separating Apparatus, of which the following is a specification.

This invention relates to flotation ore separating apparatus and its principal object resides in providing an apparatus of simple construction which in its operation produces a thorough and rapid intermixture of the ore-pulp, air and oil or other reagent, and effects a clean separation of the resultant mineral-carrying froth and the tailings associated therewith.

I attain this object by providing in combination with a container of suitable form and proportions, an air-lift which fulfills the two-fold purpose of raising the ore-pulp to a determinate elevation and of impregnating the ascending column of material with air for the purpose of producing a froth in which the mineral particles contained in the pulp are entrapped.

The discharge from the air lift enters a zone in the upper portion of the vessel in which the frothing action is completed by either the agitative influence of the constantly inflowing mixture of pulp and air, aerial agitation, or the use of mechanical stirring devices.

The stirring means in variance with those commonly employed in flotation apparatus, are designed to produce the froth by very gentle agitation thereby preventing the gangue from mixing with the value-carrying froth which rises to the surface of the liquid, and at the same time permitting it to take advantage of surface tension.

The frothing zone is surrounded by a settling zone in which the froth is collected and brought to a comparative condition of rest for the purpose of allowing the tailings associated with the froth to settle toward the bottom of the container.

The mineral bearing froth is discharged from the settling zone either by natural overflow or by the use of one or more skimmers which impel it across the edges of one or more receiving launders.

By the use of means to mechanically propel the pulp toward the ingress opening of

the air-lift, the container in which the separation process is carried on, can be made with an upright circumferential wall and a substantially flat bottom which arrangement is advantageous over the inverted cone-shaped construction of tanks of the so-called Pa-chuca type, in the elimination of pulp retaining surfaces and in permitting the use of a comparatively shallow vessel.

It will be observed that in an apparatus of the construction described, the pulp is moved to the surface of the liquid in the container once or many times. The mixture of the pulp with the air and reagent is completed as the pulp is brought to the surface and at the surface the separation takes place almost directly in opposite manner from that of the ordinary flotation cells.

The concentrates having received their buoyancy from the addition of air and oil, remain on top while the gangue settles out and sinks and inasmuch as the operation of the machine requires little power a considerable amount of pulp can be retained in the container or containers during extensive periods.

The operator is thus enabled to check the operation and has plenty of time to correct any defects due to faulty proportions of the material.

It will also be observed that in the operation of the apparatus, the heavier particles or coarse concentrates tend to sink to the bottom and are circulated more often than the lighter particles.

In this way a more frequent and complete treatment is obtained and the apparatus is thus adapted to treat the heavy concentrates quite as thoroughly as the lighter and more easily floatable material.

My improved apparatus as outlined above is obviously subject to many variations in the construction, form and arrangement of its co-operative parts, the simplest and most practical forms, at present known to me, having been illustrated in the accompanying drawings in the various views of which like parts are similarly designated, and in which—

Figure 1 is a partially sectional plan view of a settling apparatus of the improved construction,

Fig. 2, a vertical section taken along the line 2—2, Fig. 1,

Figs. 3, 4 and 5, sections similar to that

105

of Fig. 2, but drawn to a slightly reduced scale, showing modifications in the construction and arrangement of the parts of the apparatus,

5 Fig. 6, a fragmentary section showing a variation in the construction of the air-lift which forms part of the invention,

Fig. 7, an enlarged transverse section taken along the line 7—7, Fig. 6,

10 Fig. 8, a vertical section taken through the upper portion of the container and Fig. 9 a similar section of the whole container of the apparatus, illustrating modifications in the construction of the dividing wall between the frothing and settling zones of the same,

Figs. 10 and 11, sectional views showing the application of my invention to containers of the Pachuca type, and

20 Fig. 12, a sectional elevation showing the use of my improved apparatus in a series of successively connected units.

Referring first to Figs. 1 and 2 of the drawings my improved flotation ore separating apparatus comprises a cylindrical container 2 provided with a substantially flat bottom 3 and supporting a structure 4 suitable for the suspension of the rotary parts included in its construction.

25 30 A launder 5 surrounding the upper edge of the container serves to receive the overflowing froth and mineral, and auxiliary launders 6 branching radially from the peripheral launder into the container, may if necessary, be provided to expedite the collection of the supernatant froth and effect its removal before it is broken down by natural settlement.

35 40 Mounted in bearings on the structure 4, for rotation about a vertical axis aligned with the corresponding axis of the container is a shaft 7 which by means of a gearing 8 is connected with a conveniently located source of mechanical energy. The shaft carries 45 adjacent its lower end an apertured head 9 for the suspension of an open-ended conduit 10 which constitutes the major part of an air-lift through which material settling toward the bottom of the container is lifted 50 to a point adjacent the upper edge of the same.

55 The head has a number of openings through which material issuing from the upper or egress end of the conduit passes into the surrounding upper portion of the container which by means of a concentric partition 12 is divided into a central frothing zone 13 and a surrounding settling zone 14.

60 60 The partition is in the construction shown in Fig. 6 made of a downwardly flaring form principally for the purpose of promoting by surface tension, the flotation of the froth overflowing its upper edge.

A nozzle 15 projecting through a central 65 aperture in the bottom of the container, into the lower or ingress opening of the conduit 10 which is spaced from said bottom, connects with a supply of air under pressure and serves in the operation to forcibly introduce a current of air into the conduit for the two-fold purpose of lifting the material in the conduit to the egress opening at the upper end thereof, and of aerating the ascending column for the production of a froth 75 in the zone 13.

A series of sweeps 16 composed of arms which extend radially from the lower end of the conduit, are designed to impel settling material across the bottom of the container 80 toward a central point beneath the ingress opening of the air-lift, and arms 17 radiating from the shaft 7 above and in close proximity to the auxiliary launders 6, serve as skimmers to move the froth resting upon 85 the surface of the liquid in the settling zone, into said launders.

In the operation of the apparatus, the ore pulp is introduced into the container through a chute 18 which connects with an elevated 90 source of supply.

The pulp settling toward the bottom of the container is by the revolving motion of the sweeps, impelled to a central point beneath the ingress opening of the conduit and 95 compelled to ascend therein by the partial vacuum created by the current of air constantly ejected from the nozzle 15.

The pulp is aerated while it ascends toward the upper end of the conduit and may 100 at the same time be impregnated with oil or other suitable reagent introduced into the conduit together with the air issuing from the nozzle, or through a pipe separate therefrom.

The last-mentioned method of supplying the reagent has been shown in Fig. 3 in which the reference character 19 indicates a pipe extending axially in the conduit in connection with the lower end of the shaft 11 7 which in this instance is made tubular for the conveyance of a fluid introduced into the upper end thereof.

The mixture of pulp, air and reagent discharged through the upper end of the conduit into the frothing zone, is by agitation converted into a froth which overflows and passes along the flaring side of the same onto the surface of the aqueous mass in the container.

11 The liquid in the container is automatically maintained at a determinate level by a float 20 governing the movement of a valve 21 which controls the flow of a liquid through a discharge opening 22 in the circumferential wall of the container as shown in Fig. 9.

In the settling zone, the froth is brought

to a condition of comparative rest which permits of a settlement of the tailings toward the bottom of the container, while the mineral-bearing foam is collected in the launders 5 and 6.

It will be seen that in this manner a clean separation of the values and gangue in metalliferous ore-pulp is effected, it being understood that some of the tailings settle out of the material in the frothing zone although the greater part is separated by gravitation while the froth-like matter is contained in the surrounding settling zone.

The skimmers expedite the movement of the froth into the auxiliary launders, but I desire it understood that unless the froth produced in the operation of the apparatus is very light and subject to early settlement, both the skimmers and the auxiliary launders may be omitted and the froth collected by natural overflow into the peripheral launder.

The agitation of the material within the frothing zone is accomplished by either the influence of the constantly forcibly introduced ore-pulp and air, by mechanical agitation, or by the introduction of air at a point separate from the egress-opening of the conduit.

The mechanical agitation may be accomplished as shown in Fig. 4, by mounting a series of agitating blades 23 adjacent the mouth of the conduit, on a shaft 24 which extends through a tubular shaft from which the conduit is suspended and is rotated independently thereof by connection with a source of motive power at its upper end.

The mechanical agitation of the contents of the frothing zone may also be accomplished by mounting propeller blades 25 on the head 9 from which the conduit is suspended, within the frothing zone, or by providing other stirring devices of suitable design.

To agitate the material in the frothing zone by the introduction of air or other fluid, I place in the construction shown in Fig. 2, a perforated tubular ring 26 around the upper portion of the air-lift-conduit, at the end of a pipe 27 which connects with a supply of air under pressure.

In the apparatus illustrated in Fig. 3 I accomplish the same object by mounting below the frothing zone at the end of a supply-pipe 28, a hollow plate 29 whose upper surface is composed of a porous fabric through which the air issues in an infinite number of fine jets to thoroughly impregnate the ebullient mass within the zone.

In the construction shown in Fig. 5, a deflector 30 is mounted above the openings in the head 9 at the upper end of the air-conduit. This deflector which is composed of a circular, slightly concaved disk, aids

the frothing action by spreading the material issuing from the conduit and also has an agitative effect similar to that obtained by the blades 23 or 25 shown in Fig. 4.

A baffle spaced from the upper portion of the dividing wall between the frothing and settling zones, as shown in Figs. 8 and 9, may be provided to steady the movement of the froth across the upper edge of the same.

In the construction shown in Fig. 8, this baffle 31 is made in the form of an inverted conical frustum spaced from the outer surface of the similarly shaped, but reversely positioned partition 12.

In the form illustrated in Fig. 9, both the partition 12^a and the baffle 31^a are made cylindrical which under certain conditions may be preferable inasmuch as it eliminates all surfaces obstructive to the flow of material.

It will be understood that by the provision of means such as the baffles 31 for steadyng the passage of material between the zones, the width of the outer or settling zone and in consequence the diameter of the container may be reduced inasmuch as the material upon entering the said zone through the restricted passage between the baffle and the partition is immediately brought to a comparative condition of rest upon engaging the surface of the liquid in the container.

It is in many cases necessary to vary the elevation at which the material lifted in the conduit is introduced into the frothing zone.

This variation may be accomplished by any suitable adjustment of the conduit, a simple example of which is shown in Fig. 9, in which the conduit has at its upper end a longitudinal slot 32 for the egress of material.

A sleeve 33 slidably surrounding the slotted portion of the conduit, provides a gate to determine the point at which the material is discharged through the slot.

The frothing action may be still further expedited by dividing the air bubbles in the ascending column of the mixture and thereby promoting the thorough intermixture of the ore pulp, air and reagent before they enter the frothing zone.

In the form of my invention shown in Fig. 6 this object is accomplished by dividing the conduit longitudinally into a number of compartments and introducing the air separately into said compartments through a corresponding number of nozzles 35 connected with a header 36.

In Figs. 10 and 11 of the drawings I have shown my invention applied to a tapering container of the Pachuca type. Fig. 10 shows a vessel 37 made in the form of an inverted cone, and Fig. 11 illustrates a tank 38 having an upright circumferential wall and a downwardly flaring bottom 39.

In both these forms of my invention the settling material slides along the sloping surface to a central point beneath the ingress-opening of the air-lift conduit.

5 The sweeps shown in the preferred form of my invention may therefore be eliminated, and the conduit of the air-lift may if so desired be fixed with relation to the container.

10 In Fig. 10, skimmers 40 for moving the froth into the launders 6, are mounted on a shaft 42 suspended above and in axial alignment with the conduit 10, and in Fig. 11 an agitator 41 is suspended from a shaft 43 in the settling zone 13.

15 In case it is desired to complete the separation process by retreatment of the settling tailings, a series of tanks similar to that hereinbefore described may be co-operatively combined as shown in Fig. 12 by connecting the outlet of each container, except the last one of the series, with the feed opening of the next succeeding container.

Having thus described my invention what 25 I claim and desire to secure by Letters Patent is:

1. In apparatus of the character described, a container, a downwardly flaring partition dividing the upper portion thereof into a central frothing-zone and a surrounding settling-zone having an overflow for supernatant froth, and an air-lift having an ingress-opening adjacent the bottom of the container, and an egress-opening to discharge ascending material into the frothing zone.

2. In apparatus of the character described, a container, a partition dividing the upper portion thereof into a central frothing zone and a surrounding settling zone, an annular baffle spaced from said partition to provide a restricted passage for the froth from the frothing zone into the settling zone, and an air-lift having an ingress-opening adjacent the bottom of the container, and an egress-opening to discharge ascending material into the frothing zone.

3. In apparatus of the character described, a container, a downwardly flaring partition dividing the upper portion thereof into a central frothing zone and a surrounding settling-zone, an oppositely flaring annular baffle spaced from said partition to provide a restricted passage for the froth from the frothing zone into the settling-zone, and an air-lift having an ingress-opening adjacent the bottom of the container, and an egress-opening to discharge ascending material into the frothing-zone.

60 4. In apparatus of the character described, a container having in its upper portion a frothing zone and separate therefrom, a settling zone having an overflow for supernatant froth, an air-lift having an ingress-opening adjacent the bottom of the con-

tainer, and an egress-opening to discharge ascending material into the frothing-zone, and means for frothing material within the frothing-zone by aerial agitation, comprising a hollow, foraminous member in connection with a source of air-supply. 70

5. In apparatus of the character described, a container having its upper portion divided into a frothing zone and a settling-zone, an air-lift including a rotary conduit having an ingress-opening near the bottom of the container and an egress-opening for the discharge of material into the frothing-zone, a launder to receive froth collected in the settling-zone, and a skimmer connected with 80 said conduit to convey the froth into said launder.

6. In apparatus of the character described, a container having its upper portion divided into a frothing-zone and a settling-zone, an air-lift including a rotary conduit having an ingress-opening near the bottom of the container and an egress-opening for the discharge of material into the frothing-zone, and a deflector connected with the conduit 85 and disposed above the egress-opening thereof for spreading material issuing through said opening.

7. In apparatus of the character described, a container having in its upper portion a frothing-zone and separate therefrom, a settling-zone, an air-lift having an ingress-opening near the bottom of the container and an egress-opening for discharging material into the frothing-zone, and means for 100 impelling settling material across said bottom toward said ingress-opening.

8. In apparatus of the character described, a container having a substantially upright circumferential wall and a substantially 105 level bottom-surface, an annular partition dividing the upper portion of said container into a frothing-zone and a settling-zone, an air-lift having an ingress-opening near the bottom of the container and an egress-opening for the discharge of material into the frothing-zone, and means for impelling settling material across said bottom surface 110 toward said ingress-opening.

9. In apparatus of the character described, a container having a substantially upright circumferential wall, an annular partition dividing the upper portion of said container into a frothing zone and a settling-zone, an air-lift having an ingress-opening near the 115 bottom of the container and an egress-opening for the discharge of material into the frothing-zone, and means for impelling settling material across said bottom toward said ingress-opening. 120

10. In apparatus of the character described, a container having its upper portion divided into a frothing-zone and a settling-zone, an air-lift including a rotary conduit having an ingress-opening near the bottom 130

of the container, and an egress-opening for discharging material into the frothing-zone, and sweeps connected with said conduit and adapted to impel settling material toward 5 said ingress-opening by the rotary motion of the same.

11. In apparatus of the character described, a container having its upper portion divided into a frothing zone and a settling-zone, an air-lift having an ingress-opening near the bottom of the container and an egress-opening for discharging material into the frothing zone, and adjustable means for varying the elevation of the 10 egress opening of the conduit.

12. In apparatus of the character described, a container having its upper portion divided into a frothing zone and a settling-zone, an air-lift including a rotary, 20 hollow shaft and a conduit suspended therefrom and having an ingress-opening near the bottom of the container and an egress-opening for discharging material into the frothing zone, and means for introducing a 25 reagent through said shaft, into an ascending column in the conduit.

13. In apparatus of the character described, a container having in its upper portion a settling zone overflowing outside the 30 container, and a zone divided from said settling zone and overflowing thereinto, an air-lift transferring material from the bottom portion of the container into the last-mentioned zone, and means for the agitation 35 of material in the same zone after it is delivered thereinto by said air-lift.

14. In apparatus of the character described, a container having in its upper portion a settling zone overflowing outside the 40 container, and a zone divided from said settling zone and overflowing thereinto, an air-lift transferring material from the bottom portion of the container into the last-mentioned zone, and means for the aerial agita-

tion of material in the same zone after it is 45 delivered thereinto by said air-lift.

15. The combination of a subsidence vessel having an overflow, and in its upper portion, a separated zone provided with an overflow for the passage of material in 50 liquid, onto the liquid-level established by the first-mentioned overflow, a transfer conduit for the conveyance of material subsiding in the vessel to a point of discharge within said separated zone, means to effect 55 an upward flow of material in said conduit, and a device separate from said means for the agitation of material within the zone.

16. The combination of a subsidence vessel, a rotary transfer conduit for the convey- 60 ance of material settling to the bottom of the vessel, to a point of discharge above a determinate liquid level, means on said conduit for moving material toward the entrance thereof, means to effect an upward 65 flow of material in said conduit, a launder to receive floating matter skimmed off said liquid-level, and a skimmer on said conduit, to move said floating matter into the launder. 70

17. The combination of a subsidence vessel, a rotary transfer conduit for the conveyance of material settling to the bottom of the vessel, to a point of discharge above a determinate liquid level, means to effect 75 an upward flow of material in said conduit, a launder extending across the upper portion of the vessel to receive floating matter skimmed off said liquid-level, and a skimmer on said conduit, to move said floating 80 matter into the launder.

In testimony whereof I have affixed my signature in presence of two witnesses.

ALFRED L. BLOMFIELD.
